UNITED STATES PATENT OFFICE.

FRANK M. WADE, OF NATIONAL HOME, WISCONSIN, ASSIGNOR OF ONE-FOURTH TO CORNELIUS WHEELER, OF NATIONAL HOME, WISCONSIN.

FOLDING BOX.

SPECIFICATION forming part of Letters Patent No. 729,025, dated May 26, 1903.

Application filed August 6, 1902. Serial No. 118,586. (No model.)

To all whom it may concern:

Be it known that I, FRANK M. WADE, a citizen of the United States, and a resident of National Home, in the county of Milwaukee and State of Wisconsin, have invented certain new and useful Improvements in Folding Boxes; and I do hereby declare that the following is a full, clear, and exact description thereof.

10 My invention has for its object the construction of folding boxes from two strips of wood veneer or other material that can be scored and bent; and it consists in certain peculiarities of construction and combination of parts, as will be fully set forth hereinafter in connection with the accompanying drawings and subsequently claimed.

In the said drawings, Figures 1 and 2 are plan views of the said strips in their original form, the lines of scoring being indicated by the transverse dotted lines. Fig. 3 is a perspective view of the said strips bent on the lines of scoring and in position to be nested together. Fig. 4 is a sectional view of the bed and plunger of the forming-tool with the nested strips in position on the bed and the plunger in raised position ready for the next operation. Fig. 5 is a like view with the ends of one of the strips brought inward toward each other and folded by the plunger, the latter being shown in its lowered position, completing the formation of the box. Fig. 6 is a detail view of a portion of said box, showing the position the (inverted) box-bottom assumes when the plunger is again raised; and Fig. 7 is a perspective view of the finished box in inverted position.

Referring by letters to the drawings, *a* represents the bed, and *b* the plunger, of a forming-machine, whose details I have not deemed necessary to further show, as this constitutes no essential part of my invention. In Figs. 1 and 2 I show the two strips *c d*, preferably of wood veneer, scored transversely, as indicated by the dotted lines, there being double scoring on the strip *d* wherever the same has to fold over and inclose part of the strip *c* and the latter strip being formed with interlocking ends *e e*. Everywhere I have shown the box and its parts in inverted position, (as it is thus made,) and when the strips have been

bent on the lines of scoring the strip *c* has its ends interlocked and is then pushed down on the lines of the arrows in Fig. 3 and nested to place in the other strip *d*, whose central portion *f* forms the bottom of the box, and the thus united bent strips are placed on the bed *a* and the outer parts *g g* of the strip *d* brought inward (by hand or by suitable tool, as preferred) till they touch the adjacent sides of the bent strip *c*, (one of the parts *g* thus covering and protecting the interlocked ends *e e* of said strip,) which brings the extreme bent ends *h h* of strip *d* inward, and then the plunger *b* is brought down, which concaves the bottom *f* and folds the strip ends *h h* down over the edges of the adjacent sides of the strip *c*, as shown in Fig. 5, and then as the plunger *b* is again elevated the bottom *f* will spring upward and partially straighten out, thereby serving to lock the just infolded ends *h h* to place, as indicated in Fig. 6, and the completed box, Fig. 7, may now be removed from the bed.

The box I have illustrated is of substantially square shape with straight sides and ends; but it will be understood that either the sides or ends, or both, of the box may be flaring, or the box may be oblong instead of square and of any desired proportions, and the bottom may be set at any desired height in the box, as the strips and the bed and plunger of the forming-tool may be correspondingly varied according to the size and style of box desired, but otherwise made precisely as herein shown and described.

While I prefer to interlock the ends of the strip *c*, as shown and described, I may, if desired, secure these ends together in any other way, so long as I form said strip into an open frame guarded against separation in the finished box.

Having thus described my invention, what I claim as new, and desire to secure by Letters Patent, is—

A folding box formed of a pair of transversely scored and folded bent strips, one of said strips being interlocked or secured together at its ends forming an open frame held against accidental separation by such union of the ends thereof, and the second strip being nested against the said open frame, the

central portion of said second strip bearing against the opposed ends of the open frame forward of the first strip and constituting the raised bottom of the box, and the continuous 5 portions of the said second strip next the center thereof extending up from said central or bottom portion against said frame ends and thence over and down against said frame ends, with the extreme ends of said second 10 strip extending upward on the inner side of said frame ends, beneath the box-bottom and

caught between the edges of said box-bottom and the said inner sides of said frame ends.

In testimony that I claim the foregoing I have hereunto set my hand, at Milwaukee, in 15 the county of Milwaukee and State of Wisconsin, in the presence of two witnesses.

FRANK M. WADE.
